INVENTOR:

Albert Abbe Griswold

By Chas. H. Luther

ATTORNEY:

UNITED STATES PATENT OFFICE.

ALBERT ABBE GRISWOLD, OF PROVIDENCE, RHODE ISLAND.

ROLL-ROOFING FASTENER.

Application filed May 3, 1923. Serial No. 636,423.

To all whom it may concern:

Be it known that I, ALBERT ABBE GRISWOLD, a citizen of the United States, residing at Providence, in the county of Providence and State of Rhode Island, have invented a new and useful Improvement in Roll-Roofing Fasteners, of which the following is a specification.

My invention has reference to roof construction and more particularly to an improvement in means for securing roofing material, such as roll roofing, to the roofs of buildings, without the use of nails.

In the usual means for fastening roll roofing to roofs, sidings and the like, the roll roofing is usually laid in horizontal strips, lengthwise of the roof, the lower edge of an upper course overlapping the upper edge of the next lower course. The roll roofing is then secured to the roof by driving nails through it into the roof boards. The large number of nail holes thus formed in the roll roofing will cause it to leak sooner or later, thereby ruining the utility of the roll roofing and nine-tenths of all roofing leaks are caused by nail holes through the roofing material.

The object of my invention is to improve the means for securing roll roofing or the like to roofs, thereby eliminating the driving of nails through the roll roofing.

A further object of my invention is to construct such means for fastening roll roofing to roofs, whereby the upper edge portion of each under course of roll roofing is secured to the roof and the lower edge portion of each upper course of roll roofing is clamped to the roof, without penetrating the overlapping upper course of roll roofing.

My invention consists in the peculiar and novel construction of a roll roofing fastener which eliminates the use of nails for securing roll roofing to roofs and which secures the overlapping edge portion of the next upper course of roll roofing to the roof, without penetrating the same, said roll roofing fastener having details of construction, as will be more fully set forth hereinafter and claimed.

Figure 1 is a plan view reduced, of a

portion of a roof covered with roll roofing which is secured in place with my improved roll roofing fasteners.

Figure 2 is a plan view of the upper roll roofing fastener member. 55

Figure 3 is an edge view of the upper roll roofing fastener member, showing the same slightly bowed, to more firmly hold the member in place on the roll roofing. 60

Figure 4 is an enlarged detail sectional view of the upper fastening member, taken longitudinally on line 4, 4 of Figure 2.

Figure 5 is an enlarged end view of the upper fastening member. 65

Figure 6 is an enlarged detail sectional view taken on line 6, 6 of Figure 1.

Figure 7 is an enlarged side view of the lower fastening member, and

Figure 8 is an enlarged plan view of the lower fastening member. 70

In the drawing 9, 9 indicates the roof boards, 10, 10 the roll roofing of any suitable material and 11 my improved roll roofing fastener which consists of an upper fastening member 12 and an under fastening member 13. The roof boards 9, 9 may also represent the sheathing on the outer walls of the building. 75

The roll roofing 10, 10 is usually laid in strips lengthwise of the roof, first a narrow strip at the eaves edge of the roof and then the strips are laid full width, the lower edge portion of each upper course overlapping the upper edge portion of the next lower course, as shown in Figures 1 and 6. 80

The upper fastening member 12 is in the form of an elongated slightly bowed spring cleat having undeturned side edges 14, 14 85 to stiffen and strengthen the same, downwardly extending off center pointed members 15, 15 and a central depression 16, in the top cleat, as shown in Figures 2, 3, 4 and 5. This central depression 16 may be 90 in the form of a longitudinal groove if desired, for the purpose of adjusting the cleat lengthwise on the roll roofing.

The under fastening member 13 is constructed to have a thin elongated flattened body member 17 on one end of which is a comparatively long pointed member 18 at

right angles to the body member 17 and adapted to be driven through the roll roofing and into the roof boards and on the opposite end of the body member 17 is an 5 elongated hook shaped member 19, which has a downwardly formed hump 20 and a slightly upwardly turned end 21. The hook shaped member 19 lays parallel with and is spaced from the thin body 17 and 10 lays over the body 17, as shown in Figure 7.

In securing roll roofing to roofs with my improved roll roofing fasteners, a narrow strip of roll roofing is first laid along the eave edge of the roof. The under fastening 15 member 13 is placed over the upper edge portion of the strip of roll roofing and the pointed member 18 driven through the roll roofing, adjacent its upper edge and into the roof boards, until the thin body member 20 17 lays flat on the roll roofing. A plurality of the lower fastening members are thus used, securing the strip of roll roofing a predetermined distance apart, the entire length 25 of the roll roofing. The next course of roll roofing is placed on the roof and the lower edge forced under the hook shaped members 19, 19 of each under fastening member 13, 13. Upper fastening members 12, 12 are now placed on the roll roofing and an upper 30 fastening member 12 forced under each hook shaped member 19, in a position for the hump 20 on the hook shaped member 19 to snap into the depression 16 in the upper fastening member 12. This locks the upper 35 fastening member to the lower fastening member and holds the upper fastening member in place, assisted by the pointed members 15, 15 on the upper fastening member 12, which engage with the surface of the 40 roll roofing.

These operations in using my improved roll roofing fasteners are repeated for each course of roll roofing laid, thus firmly fastening down the upper edge portion of each 45 lower or underneath course of roll roofing and clamping down the lower edge portion of each upper or overlapping course of roll roofing.

By this construction the only part of the 50 roll roofing that is penetrated through into the roof boards is that part that comes under the overlapping portion of the next upper course of roll roofing, thereby eliminating nails, which are driven from the outside 55 through both courses of roll roofing and cause the roof to leak. The upper fastening member 12 is sufficiently long so as to take the place of several nails heretofore used for this purpose.

Having thus described my invention I 60 claim as new:—

1. In a roof construction and the like, overlapping strips of roll roofing, means for securing the roll roofing to the roof, 65 consisting of roll roofing fasteners, each

comprising under and upper fastening members, the under fastening member having a roll roofing and roof penetrating portion, a thin flat body portion and a hook shaped portion with locking means on the 70 hook and the upper fastening member being in the form of an elongated cleat and having means for locking it to the locking means on the hook shaped portion of the under fastening member, for the purpose as 75 described.

2. Means for fastening overlapping strips of roll roofing to roofs, consisting of roll roofing fasteners each comprising under and upper fastening members, the under 80 fastening member having an elongated thin body on one end of which is a pointed member adapted to be driven through roll roofing and into roof boards and on the other end of the body a hook shaped member parallel with and spaced from the body member, said hook shaped member having locking means, the upper fastening member being in the form of an elongated cleat with locking means, said locking means on the 85 under and upper fastening members being adapted to lock the fastening members together, for the purpose as described.

3. Means for fastening overlapping strips of roll roofing to roofs, consisting of roll roofing fasteners each comprising under and upper fastening members, the under fastening member having an elongated thin body on one end of which is a nailing member and on the other end of the body a hook shaped 95 member having locking means in the form of a hump, the upper locking member being in the form of an elongated bowed cleat having a locking member in the form of a depression in the cleat for the hump on the 100 hook of the under fastening member, said upper fastening member having under turned side edges and pointed members at each end, for the purpose as described.

4. A roll roofing fastener comprising under and upper fastening members, the under fastening member having a thin flat body on one end of which is a nailing member and on the other end of the body a hook shaped member having a hump, the upper fastening 110 member being in the form of an elongated cleat having a depression for the hump on the hook shaped member of the lower fastening member, for the purpose as described.

5. A roll roofing fastener comprising under and upper fastening members, the under fastening member having a thin flat body on one end of which is a pointed nailing member and on the other end of the body a hook shaped member, spaced from and parallel with the body and having a hump extending towards the flat body, the upper fastening member being in the form of an elongated cleat bowed lengthwise and having a central depression for the hump on the 125 130

hook shaped member of the lower fastening member, said bowed upper fastening member having undeturned side edges and an off center pointed member on each end, for the purpose as described.

6. In a two part roll roofing fastener, an upper fastening member in the form of a

bowed cleat having a central depression, undeturned side edges and an off center pointed member at each end, for the purpose as described.

In testimony whereof, I have signed my name to this specification.

ALBERT ABBE GRISWOLD.
